UNITED STATES PATENT OFFICE.

FRANK J. SCHMIDT, OF CHICAGO, ILLINOIS, ASSIGNOR TO A. STEIN & COMPANY, OF CHICAGO, ILLINOIS, A CORPORATION.

STAMPING DEVICE.

1,391,856.

Specification of Letters Patent. Patented Sept. 27, 1921.

Application filed March 10, 1921. Serial No. 451,256.

To all whom it may concern:

Be it known that I, FRANK J. SCHMIDT, residing at Chicago, in the county of Cook and State of Illinois, have invented certain 5 new and useful Improvements in Stamping Devices, of which the following is a specification.

This invention relates broadly to improvements in hand operated stamping or imprinting devices whereby an impression is made upon any suitable surface by means 10 of contact therewith by an inked type.

An object of the invention is to provide such a stamping or imprinting device with 15 means for obtaining a substantially uniform impression regardless, within certain limits, of the amount of pressure applied to the stamp in making the impression.

Another object of the invention is to prevent 20 tilting of the type and consequent smudging so common with the ordinary stamp unless extreme care is used in applying same to surface to be imprinted.

These and other objects are attained in 25 the device illustrated in the accompanying drawing in which—

Figure 1 is a side view of the entire stamp; Fig. 2 is an end view of the stamp; Fig. 3 is an end view of the stamp showing 30 type cushion compressed; Fig. 4 is a plan view of the bottom, or type face of the stamp; Fig. 5 is a detailed view in perspective of one of the side plates of the stamp.

Similar characters refer to similar parts 35 throughout the several views.

The drawing illustrates a hand operated stamp of which A is the handle, B is the body block which can be of wood or other suitable material. The said body block B is grooved on its lower surface and in said groove is secured a cushion C, which can be of cellular rubber composition or other resilient material. Upon the lower surface of said cushion C is secured by any suitable 45 means the type strip D. On each side of the body block B are the side plates E, which are secured to said body block by the rivets F. At each end of the lower edge of each side plate E is a leg or projection G, these 50 legs being of uniform length and projecting

to a plane coincident with the face of the type when said stamp is under the proper compression as shown in Fig. 3.

It will now be seen that due to the support of the legs G the pressure between the face 55 of type D and the imprintable surface will be approximately the same, substantially regardless of the amount of pressure applied to the stamp from above, thereby insuring a greater degree of uniformity in a number 60 of impressions.

It will also be apparent that due to the supporting action of the legs G there is less probability of a tipping or rocking of the stamp from a perpendicular position with 65 reference to the imprintable surface at the time of its application thereto, thus further insuring a uniformity of impression.

There are other conceivable adaptations of the principles herein disclosed and I wish 70 it understood that I do not limit myself to the structures shown and described. Therefore, what I claim and desire to secure by Letters Patent is—

1. In a device of the class described means 75 for resisting, after a degree of pressure has been established between the face of the type and the imprintable surface, further pressure between said face and said surface.

2. In a device of the class described means 80 for preventing, after a degree of pressure has been established between the face of the type and the imprintable surface, the application of greater pressure to one portion of said face than to another.

3. In a device of the class described, means 85 for resisting after a degree of pressure has been established between the face of the type and the imprintable surface, the deflection of the body of the stamp from the angle 90 at which it then rests with reference to said surface.

4. A hand stamp comprising a handle, a body, a cushion, type and means for resisting, after a degree of pressure has been established between the face of the type and the imprintable surface, further pressure between said face and said surface.

5. A stamp comprising a body member, a cushion attached thereto, type attached to 100

said cushion, and means for resisting after a degree of pressure has been established between the face of the type and the im-
printable surface, further pressure between
5 said type and said surface.

6. A stamp comprising a body member, a cushion, type, and projections from the body member, bearable upon the im-
printable sur-

face upon a partial compression of said cushion.

7. A stamp comprising a body member, compressible type, and projections from the body member, bearable upon the im-
printable surface upon a partial compression of said type.

FRANK J. SCHMIDT.
